Primary Examiner — Aula Soroush(74) *Attorney, Agent, or Firm* — ScienBiziP, P.C.(57) **CLAIM**

The ornamental design for a dog rope toy, as shown and described.

DESCRIPTION

FIG. 1 is a front, right and top perspective view of a dog rope toy, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a partial enlarged view of an area labeled 9 in FIG. 1.

The broken lines shown in the drawings are included for the purpose of illustrating portions of the dog rope toy that form no part of the claimed design.

The dot-dash line shown in FIGS. 1 and 9 framing portions of the dog rope toy for enlargement purposes forms no part of the claimed design.
